UNITED STATES PATENT OFFICE

JAMES A. YOUNG AND FRED BRYAN, OF SCIO, OREGON

MEAT SAW

Application filed June 17, 1930. Serial No. 461,770.

The present invention relates to a meat saw and has for its prime object to provide a power driven saw in this nature which is exceedingly simple in its construction, light, 5 strong and durable, compact and convenient in its arrangement of parts, easy to manipulate, thoroughly efficient and reliable in use and operation, easy to assemble and disassemble and saw blade from the remaining portion 10 of the mechanism, and otherwise well adapted to the purpose for which it is designed.

With the above and numerous other objects in view as will appear as the description proceeds, the invention resides in certain novel 15 features of construction, and in the combination and arrangement of parts as will be hereinafter more fully described and claimed.

In the drawings:

Figure 1 is a sectional side elevation of the 20 saw structure embodying the features of our invention,

Figure 2 is a sectional view through one end thereof,

Figure 3 is a detail section taken substantially on the line 3—3 of Figure 2,

Figure 4 is a perspective view of one of the saw blade attaching blocks.

Figure 5 is a transverse section taken substantially on the line 5—5 of Figure 1,

Figure 6 is a similar view taken substantially on the line 6—6 of Figure 1, and

Figure 7 is a perspective view of the externally screw threaded sleeve to which one end of the cable is attached.

Referring to the drawings in detail it will be seen that the letter F denotes generally an elongated frame which in the present instance this frame F comprises an elongated straight hollow upper rail 5 which merges at 40 its ends into arcuate channel end rails 6 which in turn merge into bottom rail segments 7 terminating in spaced relation to each other and of channel construction having inwardly directed flanges 8.

Braces 9 extend between the terminals of

the sections 7 and intermediate portions of the rail 5. A housing 10 is formed on one end portion of the rail 5 and has a double spiral grooved rotor 11 journaled therein with an extension 12 adapted to be connected to a power driven cable shaft or the like. A block 14 is slideable in said end portion of the rail 5 and has a pin 15 projecting into the groove of the rotor 11 so that when the rotor 11 is in motion the block 14 reciprocates back and forth.

Cables 16a are connected with the block 14 and trained over keys or pulleys 16 journaled in the end rails 6 as clearly illustrated in Figure 2. On the ends of the cables are externally threaded sleeves 18 adapted to be received in blocks 19 mounted for reciprocation in the rail sections 7.

These blocks 19 have reduced extensions 20 from the ends of which rise spaced parallel ears 21. Blocks 22 have reduced ends split to form spaced parallel furcations 23 having notches 24 in intermediate portions of their upper edges. The reduced portion 23 is pivotally mounted as at 25 between the ears 21 and the block 22 is adapted to be locked on the portion 20 by a screw 26. Numeral 27 denotes a meat saw blade, the ends of which have laterally extending pins 28 to be received in the notches 24 and then the blocks 23 are swung downwardly and locked on the reduced portions 20 and the saw is ready for operation causing reciprocation back and forth of the saw blade.

A bowed spring 30 is anchored as at 31 on one end rail 6 and projects through one brace 9 and terminates in abutment with the upper edge of the saw blade 27.

It is thought that the construction, operation, utility and advantages of this invention will now be quite apparent to those skilled in this art without a more detailed description thereof.

The present embodiment of the invention has been disclosed in considerable detail

merely for the purposes of exemplification since in actual practice it attains the features of advantage enumerated as desirable in the statement of the invention and the above description.

5 It is apparent that changes in the details of construction, and in the combination and arrangement of parts may be resorted to without departing from the spirit or scope 10 of the invention as hereinafter claimed or sacrificing any of its advantages.

Having thus described our invention, what we claim as new is:

1. A saw structure of the type embodying 15 an elongated frame having an upper hollow elongated straight rail merging at its ends into arcuate end rail channeled construction which in turn merge into inwardly directed bottom channeled rail sections terminating 20 in spaced relation to each other, a plurality of guide pulleys journaled along the curve of the end rails, cables in the rails trained over the pulleys, a saw between the ends of the cables, and means in the form of a rotor 25 disposed longitudinally upon the upper rail and having a double spiral groove therein for receiving a pin projecting from a block slidably disposed thereunder in the upper rail to which the said cable is secured, where- 30 by to reciprocate a saw blade slidably maintained between the mentioned bottom channeled sections.

2. A saw structure of the type described 35 embodying an elongated frame composed of an upper hollow elongated straight rail having at its end arcuate end rails of channeled construction which in turn merge into inwardly directed bottom channeled rail sections terminating in spaced relation to each 40 other and parallel to the upper rail, a plurality of guide pulleys journaled in the end rails, and spaced apart, cables in the rails trained over the pulleys, a saw between the ends of the cables, and means mounted on the upper rail in the form of a rotor having a double spiral groove therein for receiving a pin from a block slidably in the upper rail and under the rotor, having said cables attached thereto whereby to reciprocate the 45 saw.

3. A saw structure of the type described 55 comprising a frame consisting of a straight elongated tubular body having on each end a merging dependent outwardly opened arcuate channel, on the lower inward end of which extends inwardly and parallel to the tubular body a tubular bearing extension, a saw blade having a bearing block on each end slidable in one of said tubular exten- 60 sions, a plurality of arcuately spaced guide pulleys in each of said arcuate channels, a cable led over the pulleys in each channel from each of said bearing blocks, and means for moving said cables to reciprocate the 65 saw, comprising, a cylindrical housing

mounted upon said tubular body adjacent one arcuate channel having journaled there- 70 in a rotor formed with twin spiral grooves for slidably receiving a pin on a block slid- able in the tubular body under said rotor, said cables being connected to said slidable block.

In testimony whereof we affix our signatures.

JAMES A. YOUNG. 75
FRED BRYAN.
